UNITED STATES PATENT OFFICE.

JOHN F. STANDISH, OF WINTHROP, MASSACHUSETTS, ASSIGNOR TO UNITED SHOE MACHINERY COMPANY, OF PATERSON, NEW JERSEY, A CORPORATION OF NEW JERSEY.

MACHINE FOR MAKING BLANKS FOR HEELS.

1,126,903.

Specification of Letters Patent.

Patented Feb. 2, 1915.

Application filed February 14, 1912. Serial No. 677,540.

To all whom it may concern:

Be it known that I, JOHN F. STANDISH, a citizen of the United States, residing at Winthrop, in the county of Suffolk and 5 State of Massachusetts, have invented certain Improvements in Machines for Making Blanks for Heels, of which the following description, in connection with the accompanying drawings, is a specification, like 10 reference characters on the drawings indicating like parts in the several figures.

This invention relates to improvements in the art of making blanks or logs of leather-board or other fibrous composition for use 15 in the heels of boots and shoes.

It is an object of the invention to provide a machine by the use of which such heel blanks or logs may be produced directly from leather-board pulp as distinguished 20 from the blanks or logs heretofore constructed by uniting a number of separate layers of leather-board.

To this end an important feature of the invention consists in the provision of a mold 25 carrier having molds of the shape desired in the blanks to be produced and means for feeding leather-board pulp from a tank in which it is contained in suspension into the molds of the carrier where it is compressed 30 and shaped. By employing a machine of this type it is possible to produce an integral heel blank of any desired height or shape and therefore numerous steps which have been necessary heretofore in the production 35 of finished heels are eliminated.

It has been found that the best results are secured by delivering the leather-board pulp to the molds in thin successive layers or 40 films and by pressing each layer firmly upon the previously received material in order that its fibers may become interwoven therewith and a firm homogeneous article result.

To this end, another important feature of the invention consists in the provision of 45 pressing means within the molds arranged to subject each successive layer of pulp to pressure as it is received. As herein shown the mold carrier comprises a cylinder and the separate molds extend inwardly from 50 its periphery and are each provided with a presser plate. The mold carrier rotates in engagement with a roller and the pulp is delivered to the molds and pressed into them against the presser plates by being intro-

duced between the roller and mold carrier. 55 An endless apron or belt affords a convenient means for feeding the pulp to the molds.

In starting the building operation the presser plates are arranged to project slightly beyond the periphery of the mold 60 carrying cylinder so that they are forced yieldingly inwardly when they engage the layer of pulp upon the apron between themselves and the roller. In accordance with the present invention it is proposed to make 65 the entrance to each mold of smooth material, such as polished brass, to which the pulp will not adhere and to make the presser plates of rougher material, such as cast iron, which will become coated with pulp. 70 After the presser plate has been once coated the successive layers of pulp will adhere to the compressed pulp held on the plate rather than to the smooth portion of the mold carrier with which it comes in contact. It will 75 be seen that at each rotation of the mold carrying cylinder a new layer of pulp is deposited upon the presser plate which, in turn, is forced into the mold as the blank gradually increases in thickness. During 80 the building process it is important to prevent the outward movement of the presser plates in the molds as this would eject the partially completed blanks.

To this end another feature of the invention 85 consists in the provision of presser plates which are arranged for inward movement in opposition to the action of compression springs but which are automatically locked against outward movement.

The invention includes, as another important feature, means for releasing the presser plates when blanks of sufficient thickness have been built in order that the finished blanks may be ejected from the ma- 95 chine.

Another feature of the machine relates to provision for handling the finished blanks when they are ejected and for conveying them away from the machine in which they 100 are built. As herein shown this is effected by arranging an endless conveyer to run adjacent to the mold carrying cylinder and to receive the blanks directly from the molds and convey them to a drying room or other 105 place desired. Preferably the conveyer will be provided with shelves spaced to correspond with the spacing of the molds, and

in this case each row or tier of molds will empty itself into a separate shelf on the conveyor.

These and other features and advantages incident to the invention will be best understood and appreciated from the following description of a preferred embodiment thereof selected for purposes of illustration and shown in the accompanying drawings in which,—

Figure 1 is a view of the machine in side elevation; Fig. 2 is a front view of the machine partly in section; Fig. 3 is a view in perspective of the blank pressing member; Fig. 4 is a view in perspective of one section of the drum showing the molds; Fig. 5 is a detail view of the mold locking device; Fig. 6 is a view in perspective of a mold and presser plate for building a heel log.

The operation of the machine will be best understood from a brief description of its general organization and the manner in which its parts coöperate. Referring particularly to Figs. 1 and 2, it will be seen that the machine comprises a frame 2 having journal bearings for the shaft 4, upon which is mounted the roller 6, and for the upper shaft 10 carrying drum or cylinder 12 in which the heel blanks are formed. At one side of the machine is located the tank 52 in which is contained the leather-board pulp. An endless belt or apron 50 running over suitable rollers receives the pulp from the tank and conveys it between the lower roller 6 and the cylinder 12. In passing between the roller and cylinder the film of leather-board pulp on the apron adheres to the pressing plates 14 in the molds 16 of the cylinder 12 and is removed from the apron 50. The leather-board pulp gradually builds up on the presser plates 14 forcing them inwardly in the molds against spring pressure. During the building operation the presser plates are locked against outward movement and are released only when blanks of sufficient thickness have been produced in the molds. When this condition is reached the pressing plates are released and the finished blanks are ejected into a traveling conveyor 100 by which they are carried to the drying room.

Having briefly outlined the operation of the machine its details of construction will now be more particularly described.

Motive power to run the machine is supplied by the belt 21 to a pulley 20 fast on a shaft 22 journaled at one side of the frame 2 and carrying a gear wheel 24 which meshes with a larger gear wheel 26 on the shaft 4 of the lower roller 6. Above and within the tank 52 are provided suitable rollers, over which runs the endless apron 50 of textile material. The outer roller 56 carries the apron into engagement with a transferring drum 57 which is partly submerged in the

tank 52 and which serves to collect the pulp from the tank and from the incoming stream of fresh pulp and transfer it to the apron. From the roller 56 the apron runs between the cylinder 12 and bottom roller 6, then downwardly about the roller 6 and back partly through the tank to the roller 56.

The cylinder 12 is driven from a sprocket wheel 28 which is secured to a gear wheel 29 and with it turns loosely on the opposite end of the shaft 4 from the gear wheel 26. The end of the cylinder shaft 10 is provided with a sprocket wheel 30 over which runs a sprocket chain 32 which passes also about the sprocket wheel 28. The gear wheel 29 is driven in the proper direction through an idler 31 by a gear wheel similar to the gear 24 but upon the end of the shaft 22 not shown in the drawings. As the cylinder 12 and the sprocket wheel 30 are vertically movable with respect to the sprocket wheel 28 there is provided an idle pulley 34 mounted on the arm 36 which is arranged to swing outwardly under the actuation of the spring 38 and so take up any slack in the sprocket chain 32.

The frame 2 has upwardly extending standards provided with vertical guideways for journal boxes 8 of the shaft 10 and these boxes rest normally upon adjustable stops 40 set in the frame 2 and are pressed downwardly by stiff compression springs 42 interposed between the top of the bearing boxes 48 and vertically adjustable plates 44.

The cylinder 12 is composed of a plurality of sections held in place by bolts 13 extending through the heads of the cylinder. In each section are formed a series of molds 16. The molds 16 extend inwardly from the surface of the section for a distance somewhat greater than the thickness of any heel blanks which it might be desired to build. At the inner ends of the mold 16 the section is cut away to receive a presser bar 60 having a plurality of shanks 61 upon each of which is mounted a presser plate 14 having the shape of a mold. From the inner side of the presser bar 60 projects a pair of rods 62 each of which is surrounded by a compression spring 18 bearing at its inner end against a bar 64 comprising a stationary part of a section and having sockets to receive the springs 18. The springs 18 therefore act to force the presser bar and the presser plates 14 outwardly, their action being overcome gradually as the leather-board pulp accumulates upon the face of the presser plates 14 and forces the plates inwardly.

The outer ends of the molds, where they extend to the periphery of the mold carrying cylinder, are provided with a raised beading 15 which is rounded and smoothed or polished so that the pulp will have no

tendency to adhere to the outer surface of the sections.

It is important to provide means for preventing outward movement of the presser plates during the heel building operation and one desirable means for effecting this result is illustrated hereina. As shown in Fig. 2 there is provided a tapering socket 66 in each side of the sections adjacent to the sides of the presser bar 60 and in each of these sockets is disposed a roller 68. The sockets 66 taper outwardly and the rollers 68 are yieldingly moved toward the shallower end of the grooves by the forked angle levers 70. The rollers 68 therefore jam between the sides of the presser bar 60 and the bottom of the sockets in such manner as to prevent outward movement of the presser bar 60 but leave it free to move inwardly. The forked levers 70 are acted upon by compression springs 72 which tend to swing their outer ends away from the cylinder head. When it is desired to release the presser bar 60 and permit the blanks to be ejected from the molds it is necessary only to swing the ends of the levers 70 inwardly so that the rolls 68 shall be carried into the wider ends of the grooves 66. A preferred mechanism for releasing the presser bar 60 is shown in Figs. 1 and 5. A trip arm 74 is pivotally mounted on a rod 76 set in the side of the frame and is normally pulled outwardly by a compression spring 79 acting on a pin 77 pivotally connected to the trip arm. The outer end of the trip arm stands in the path of a cam piece 78 fast to the upper end of a rod 80 pivotally connected to the hand lever 81. The hand lever is normally held in an elevated position by the tension spring 82. When the lever 81 is depressed the cam piece 78 is moved downwardly and the trip arm 74 swung inwardly into the path of the other ends of the forked levers 70 as they are carried past the trip arm by the rotation of the cylinder 12. It will be understood that the levers 70 on the end of the cylinder not shown in Fig. 1, are released by the operation of the hand lever 81 simultaneously with the release of those on the near end of the cylinder. To effect this result the lever 81 is keyed to a transverse rockshaft 83 which carries at its other end a short arm and cam piece arranged to operate on a trip arm similar to the trip arm 74 shown in Fig. 1.

When the presser plates are released the presser bar 60 is moved outwardly until it encounters the inner ends of the partitions between the molds 16 which prevent further movement. In this position of the presser bar the presser plates are substantially flush with the outer surface of the raised beading 15.

The finished blanks are ejected from their molds into the traveling conveyer 100 by the

action of the springs 18. The conveyer runs over a drum 90 fast to the shaft 92 which has on one end a sprocket wheel 93 connected through the chain 94 with a sprocket wheel not shown but arranged to rotate with the idler 31. The conveyer is provided with a series of shelves or pockets 102 and on account of the positive connection between the cylinder and the drum 90 through the gearing above described the shelves 102 are maintained in the proper relation with the sections of the cylinder to receive the ejected blanks. Accordingly when the hand lever 81 is held in a depressed position, each section automatically empties itself into a successive shelf on the conveyer. The conveyer may be extended to any convenient point and the blanks thereby delivered directly to the drying room, if desired.

In the foregoing description reference has been made to "heel blanks" but it should be understood that the machine herein shown is adapted, without material change, to be used in producing separate lifts rather than entire heel blanks, as the thickness of the blanks depends primarily upon the interval occurring before the hand lever 81 is operated. The shape of the molds is immaterial to the operation of the machine and in case blanks of different shapes are required, they may be readily produced by substituting other sections having differently shaped molds. If, for example, it is preferred to build a heel log instead of separate heel blanks in the machine herein shown, sections similar to those illustrated in Fig. 6 may be substituted for the sections having the individual molds. As shown in Fig. 6 the section is provided with a mold extending across the whole width of the cylinder and the presser bar 60 is provided with a single pressing plate 150. In such a section therefore a slab or log will be built the length of which is equal to that of the cylinder 12. Such a slab is adapted to be cut or sawed up subsequently into separate heel blanks.

Having described my invention, what I claim as new and desire to secure by Letters Patent of the United States is:—

1. A machine of the class described having, in combination, a carrier having a plurality of separate molds, means for delivering successive layers of pulp to each mold and means movable relatively to the molds for mechanically pressing the contents of the mold at each delivering operation.

2. A machine of the class described having, in combination, means for collecting a continuous layer of pulp, and means for removing successive portions of the pulp from the collecting means and shaping them into separate blanks.

3. A machine of the class described having, in combination, means for collecting

- layer of pulp, and means for removing successive portions of the pulp from the layer and, simultaneously with their removal, pressing them to shape them into separate blanks.
4. A machine of the class described having, in combination, an endless apron for collecting and conveying a layer of pulp, a pair of oppositely disposed rollers between which the apron runs, and a circumferential series of molds in one of the rollers for receiving pulp from the apron.
5. A machine of the class described having, in combination, a tank for containing leather-board pulp in suspension, a cylinder having a series of separate molds, a presser plate in each mold, and means for conveying the pulp from the tank and delivering it to the molds.
6. A machine of the class described having, in combination, a mold having therein a presser plate mounted to yield relatively thereto, and means for successively forcing layers of pulp into the mold against the action of the presser plate.
7. A machine of the class described having, in combination, a mold having a presser plate arranged for yielding movement inwardly but being automatically locked against outward movement, and means for delivering material to be shaped to the mold.
8. A machine of the class described having, in combination, a cylinder having a plurality of circumferentially arranged molds therein, a roller arranged to run in engagement with the cylinder, means for yieldingly forcing the cylinder and roller toward each other, and means for introducing pulp between the roller and cylinder in order that it may fill the molds.
9. A machine of the class described having, in combination, a cylinder for molding leather-board having oppositely disposed heads, and removable sections secured to the head, each section having a series of separate molds and a presser plate within each mold.
10. A machine of the class described having, in combination, a mold carrying cylinder having a plurality of mold cavities in its periphery and a smooth raised portion surrounding the outer end of each cavity.
11. A machine of the class described having, in combination, a cylinder having molds formed in its periphery and a smooth portion surrounding the opening of each mold, together with movable presser plates located in each mold.
12. A machine of the class described having, in combination, a cylinder having a plurality of molds, a presser plate in each mold, springs acting to force each presser plate outwardly in its mold, and means acting normally to prevent movement of the presser plates outwardly but permitting their movement inwardly.
13. A machine of the class described having, in combination, a cylinder having a plurality of molds, pressing means within each mold, locking devices acting normally to prevent the outward movement of the pressing means, and means for rendering inoperative the locking devices.
14. A machine of the class described having, in combination, a carrier having a plurality of mold sections, each section comprising a series of separate mold cavities extending inwardly from its surface and having a chamber located at the inner ends of the cavities, a presser bar disposed within the chamber, and presser plates secured to the presser bar.
15. A machine of the class described having, in combination, a rotatable carrier having molds spaced upon its periphery, a conveyor having shelves spaced from each other by distances equal to the spacing of the molds, and means for positively driving the carrier and conveyor in such relation that the molds and shelves shall be in register.
- In testimony whereof I have signed my name to this specification in the presence of two subscribing witnesses.
